UNITED STATES PATENT OFFICE.

FRANK J. GIBBS, OF PHILIPSBURG, PENNSYLVANIA.

REIN-HOLDER.

SPECIFICATION forming part of Letters Patent No. 351,758, dated November 2, 1886.

Application filed March 17, 1886. Serial No. 195,527. (No model.)

To all whom it may concern:

Be it known that I, FRANK J. GIBBS, of Philipsburg, in Centre county, and State of Pennsylvania, have invented a new and useful Improvement in Rein-Holders, of which the following is a specification, reference being had to the annexed drawings, forming a part thereof, in which—

Figure 1 is a perspective view of my improved rein-holder. Fig. 2 is a longitudinal section showing the attachment of the rein-holder to the rein. Fig. 3 is a longitudinal section showing the position of the parts when the rein is released.

Similar letters of reference indicate corresponding parts in the different figures of the drawings.

The object of my invention is to provide a simple, easily attached, and efficient hand-holder or rein-holder.

My invention consists in a buckle adapted to be clamped on the rein, and provided with a loop for receiving the hand of the driver.

The frame A, forming the body of the buckle, consists of the end pieces, a, and the cross-bars b, b', and c, the cross-bar c being cylindrical in form and raised above the plane of the bars b b'. Upon the cross-bar c is journaled a right-angled lever, B, having a long arm, d, and a short arm, e, the short arm being of sufficient length to project slightly below the plane of the bars b b'. A loop, f, having its ends turned inward and inserted in the holes of the end pieces, a, receives the leather loop C on that part parallel with the cross-bar c, and also receives loops g, formed on the ends of a stirrup, h, which embraces the longer arm, d, of the right-angled lever B.

By moving the loop f, and with it the lever B, into the position shown in Fig. 3, the rein

may be readily inserted in the buckle between the bars b b' and the right-angled lever B, when the loop f may be moved forward into the position shown in Fig. 2, bringing the shorter arm of the right-angled lever B into engagement with the rein D, and also clamping the rein between the longer arm of the right-angled lever B and the cross-bar b'. The increased tension on the rein in the direction indicated by the arrow tends to increase the pressure of the longer arm, d, of the lever B upon the rein, thus holding it with a degree of pressure corresponding with the requirements. By turning the loop f outward, as shown in Fig. 3, the buckle may be moved along the rein to any desired position, and it may be readily secured by simply pulling on the loop C.

Having thus described my invention, what I claim as new, and desire to secure by Letters Patent, is—

1. The combination, in a rein-holder, of the frame A, formed of end pieces, a, cross-bars b b' c, connecting the end pieces, the loop f, pivoted in the end pieces, a, the right-angled lever B, turning on the cross-bar c, and the stirrup h, connecting the loop f and the lever B, substantially as herein shown and described. 6c

2. The combination, in a rein-holder, of the frame A, formed of end pieces, a, cross-bars b b' c, connecting the end pieces, the loop f, pivoted in the end pieces, a, the right-angled lever B, turning on the cross-bar c, the stirrup h, connecting the loop f and the lever B, and the leather loop C, resting on the loop f, substantially as herein shown and described. 70

FRANK J. GIBBS.
